UNITED STATES PATENT OFFICE.

HARRY W. BOLENS, OF PORT WASHINGTON, WISCONSIN.

ONE-PIECE METALLIC GALLEY.

1,420,363.

Specification of Letters Patent. Patented June 20, 1922.

Application filed November 22, 1920. Serial No. 425,727.

To all whom it may concern:

Be it known that I, HARRY W. BOLENS, a citizen of the United States, and resident of Port Washington, in the county of Ozaukee 5 and State of Wisconsin, have invented certain new and useful Improvements in One-Piece Metallic Galleys; and I do hereby declare that the following is a full, clear, and exact description thereof.

10 My invention refers to printers' galleys, and it has for its primary object to provide a simple, economical and convenient galley which is formed from a single sheet of metal.

15 The specific objects of my invention are: To provide a rectangular one-piece metallic galley, wherein the vertical end and side walls are folded upwardly without breaking or interrupting the corners.

20 To provide means associated with the walls and bottom of the galley for supporting said galley bottom above the table or slab upon which the galley rests.

25 To provide a depending tubular bead or flange for accomplishing the desired bottom support, which tubular bead also serves as a gutter adapted to collect moisture from the bottom of the galley, or dust accumulations, it being obvious that the hollow bead also 30 materially strengthens the galley throughout.

35 To provide the hollow bead in such relation to the bottom that it merges into the lower edge of the vertical side and end walls, in such formation as to align the inner contact walls of the sides and ends directly over the terminal edge of the bottom, it being understood that the edge of the bottom, side 40 walls and end walls, are complementary, whereby type resting upon the bottom will be aligned by said side and end walls.

45 With the above and other minor objects in view, the invention consists in certain peculiarities of construction and combination of parts, which are herein set forth, with reference to the accompanying drawing and subsequently claimed.

In the drawing:

50 Figure 1 represents a plan view of a one-piece metallic galley embodying the features of my invention,

Figure 2 is a cross section of the same,

the section being indicated by line 2—2 of Figure 1, and

55 Figure 3 is a fragmentary sectional view of another form of my invention.

Referring by characters to the drawing, 1 represents a rectangular flat bottom, 2 a vertically disposed end wall, and 3, 3' complementary side walls, the same being parallel and merged into the end wall to form 60 rectangular uninterrupted corners 4, 4'.

One end of the galley, in this exemplification of my invention, is shown open, but 65 obviously in some instances it may be provided with a wall corresponding to the end wall 2.

The outer edges 5 of the rectangular bottom plate 1, are in approximate alignment 70 with the inner faces of the vertical walls previously mentioned, whereby type resting upon said bottom will come in contact with and be supported by said wall faces.

As shown in Figure 2, the vertical 75 walls of the rectangular one-piece galley, at their lower ends, are flared outwardly and are merged into a hollow bead or gutter 6. The inner wall 6' of this gutter merges into the outer edge of the bottom to form more 80 or less abrupt corners, which corners assume a plane, in vertical alignment with the inner faces of the end and side walls.

85 Thus it will be seen that the metal blank, when pressed into shape, will form a hollow bead, which projects below the surface of the bottom and follows its outer edges to constitute a drained gutter for moisture, and it also forms a reinforced supporting 90 rib for the galley, whereby the galley bottom is spaced above the table or slab upon which it would otherwise rest.

95 This hollow bead solves the problem of rigidity which is necessary in a galley of this type wherein thin metal is used. It also solves the problem of a drainage for accumulating moisture due to variations of temperature, and also resulting from dampness. It further solves the problem of protecting the bottom 1 against puncture, due 100 to the fact that frequently loose type upon the table or slab, will come in contact with the bottom and either dent the same or puncture it, in instances where the bottom rests solidly upon the table or slab. Furthermore, even though the type did not 105

puncture the bottom, when the metallic galley is moved, there is a constant grind under the bottom in instances where it rests upon a type, which tends to buckle the 5 metal or otherwise injure the device.

While I have shown and described one exemplification of my invention, wherein the hollow bead is substantially U-shaped in cross section, obviously the shape of the 10 bead may be varied indefinitely, within the knowledge of skilled mechanics to accomplish the same general result.

Particular attention is also called to the fact, that owing to the simple construction, 15 wherein the reinforced hollow bead is produced, that a one-piece metallic galley can readily be formed by die methods or it may be cast, and also owing to the simplicity of construction the corners of the 20 rectangular structure can readily be formed without breaking or interruptions when the metal is drawn upwardly to form the end and side walls.

As previously stated, the hollow bead, 25 being below the bottom surface, accumulation from the moist type is assured, and

such moisture and dust that may collect is readily trapped or deflected into the gutter. Hence the type at all times is firmly seated upon the bottom 1 and against the 30 inner faces of the vertical walls.

I claim:

A one-piece metallic rectangular galley comprising a flat bottom, a peripheral portion directed downwardly therefrom for a 35 short distance, a horizontal portion outwardly directed for a short distance from said peripheral portion and thence upwardly for a short distance and bent inwardly to a point in line with the outward 40 vertical face of the side peripheral portion and extending straight upward therefrom so that sides are formed, the inner faces 45 of which are upon a plane approximately paralleling the terminal edges of the bottom and insure side and end supports for printer's type.

In testimony that I claim the foregoing I have hereunto set my hand at Port Washington, in the county of Ozaukee and State 50 of Wisconsin.

HARRY W. BOLENS.
